UNITED STATES PATENT OFFICE.

GEORGE H. FORSYTH, OF CHICAGO, ILLINOIS.

METAL SASH CONSTRUCTION.

1,405,829.

Specification of Letters Patent. Patented Feb. 7, 1922.

Application filed October 3, 1914. Serial No. 864,705.

To all whom it may concern:

Be it known that I, GEORGE H. FORSYTH, a citizen of the United States, residing at Chicago, in the county of Cook and State 5 of Illinois, have invented certain new and useful Improvements in Metal Sash Constructions, of which the following is a specification.

The present invention has for its object 10 the provision of a simple, efficient and compact window construction involving more particularly though not exclusively the employment of a narrow metal sash in connection with the necessary hardware and 15 other fittings such as locks, weather stripping, glazing beads, etc., whereby to adapt such accessories to the limitations involved in the way of small space for mounting and freedom from interference one with another, and with the operation of the narrow 20 sash within the guides formed by the sash stops.

Metal sash are of two general types, those having a removable glazing bead and those in which the glass is confined between two beads neither of which is removable. Where the sash is of sufficient width to accommodate the lock on its side face no difficulty is encountered in mounting the same, but when the width of the sash is reduced to the narrowest dimensions, first in order to save metal and to increase the glazed area for the admission of light, the inner edge of the sash adjacent the glass must be utilized in the mounting of the lock and this gives rise to the problem of harmonizing the necessity of a secure anchorage for the lock with the convenient glazing of the sash and the prevention of the passage of the elements around the edges of the sash.

It is often required that the sash be glazed without removal of the sash from the opening, which latter may be very difficult in view of the construction of the sash opening and adjacent car structure. Hence the necessity of a removable glazing bead, which frequently has to be provided upon the same side of the sash as the lock or other sash attachments are located. This invention is intended to meet these conditions, as well as to improve the manner of mounting the lock upon a fixed sash bead. Other associated features of invention will also be brought out.

In the accompanying drawings and in the detailed description based thereon are set

forth preferred and modified embodiments of the invention. As, however, the invention is capable of embodiment in other and varied constructional forms than those 60 shown, it will be understood that the drawing and description are to be taken in an illustrative and not in an unnecessarily limiting sense. In the drawings—

Fig. 1 is an elevation of a corner of a 65 sash showing a lock mounted upon the inner edge of a sash and cooperating with the usual glazing bead to effect the retention of the glass;

Fig. 2 is a vertical section on the line 70 2—2 of Fig. 1;

Fig. 3 is a similar section on the line 3—3 of Fig. 1;

Fig. 4 is a horizontal section on the line 4—4 of Fig. 1; 75

Fig. 5 is a detail cross sectional view of the form of removable glazing bead shown in Figures 1 to 4;

Fig. 6 is an elevation of a sash corner showing the lock mounted upon the fixed 80 glazing bead;

Fig. 7 is a vertical transverse section on the line 7—7 of Fig. 6;

Fig. 8 is a horizontal transverse section on the line 8—8 of Fig. 6; 85

Fig. 9 is a section similar to Fig. 8 showing a slightly modified construction in which the removable glazing bead and weather strip are combined in one;

Fig. 10 is a fragmentary view in elevation of a sash corner on that side opposite the lock and showing the relation of the glazing bead and weather strip at the corner of the sash; 90

Fig. 11 is a front elevation of a sash corner showing the lock permanently mounted upon the removable glazing bead, the whole being removably mounted upon the sash;

Fig. 12 is a vertical transverse section on the line 12—12 of Fig. 11; 100

Fig. 13 is a horizontal transverse section on the line 13—13 of Fig. 11;

Fig. 14 is a front elevation of a sash corner showing a modified form of mounting the lock upon the fixed bead of the sash in interlocked relation; 105

Fig. 15 is a vertical transverse section on the line 15, 15 of Fig. 14;

Fig. 16 is a horizontal transverse section on the line 16—16 of Fig. 14; 110

Figs. 17 and 18 are fragmentary perspective views of the sash members underlying

the lock and illustrating the provision for an interlocking connection between the lock and sash;

Fig. 19 is a horizontal transverse section 5 through the sash stile showing a modified form of glazing bead; and

Fig. 20 is a horizontal section showing a slightly modified form of construction.

Having reference more especially to Figs.

- 10 1 to 5 inclusive of the drawing the reference numerals 21 and 22 designate the sash rail and stile respectively connected together to form a sash corner, the rail and stile each including a fixed bead 23 for the retention of
- 15 the glass 24 the margin of which abuts on its four sides against said bead as will be readily understood. The sash members 21 and 22 on the side opposite the bead 23 have no flange or bead so as to permit the glass to be
- 20 inserted from that side. In order to hold the glass in position a glazing bead designated generally at 25 is provided which is in the form of a spring metal strip having one portion of substantially U-shape, the side walls
- 25 26, 27 of the U being normally inwardly sprung towards each other as shown in Fig. 5 and the bottom 28 of the U having an oblique relation to the side walls while the remainder of the glazing bead consists of a
- 30 portion 29 slightly inclined to the vertical, a portion 30 slightly inclined to the horizontal, and an underlying portion 31. The U portion of the strip is adapted to be slipped over the edge of the glass as indicated in
- 35 Figures 3 and 4, the converging relation of the walls causing the same to hug the side face of the glass while the oblique bottom of the U provides a clearance which imparts centering resiliency to the glass in the
- 40 plane thereof. The glazing bead having been fixed to the edges of the glass the latter with the bead is inserted in the sash and pushed back against the fixed bead 23. In so doing the oblique bottom of the U forms a
- 45 close fit with the plane face of the sash and screws 32 passing through and inclined slightly to the plane of the approximately horizontal portion 30 causing the walls 25 and 29 to more snugly abut against the glass
- 50 while clamping the bead to the sash member. It will thus be seen that the glazing bead provides for the resilient mounting of the glass and for the hermetic sealing of the sash against the penetration of the elements
- 55 around the edge of the glass.

As practically the entire side face of the sash stile lies within the sash guide and below the level of the stop 33 it is impossible to attach the lock to the side face of the 60 stile and it is also impracticable to permit the lock to encroach upon the side face of the rail sufficiently to utilize the side face as a principal means of connection for the lock to the rail. In this form of construction 65 therefore I mount the lock upon the inner

edges of the rail and stile and utilize the flanged portions 34 and 35 of the lock to perform the function of a glazing bead at the corner of the sash, these flanges bearing against the outer marginal face of the glass 70 and the lock being secured to the inner edge of the sash members by the screws 36 and 37 while additional screws 38 may be employed upon the outer face of the rail, the same passing through the depending flange 75 39 of the lock.

In order to accommodate the lock in this position and permit it to perform this glazing function, the glazing beads proper do not extend to the corner of the sash but terminate at the edges of the lock and abut against the flanges 34 and 35 of the latter.

In order to effect a rigid connection between the sash members at the corner, tubular L-shaped metal inserts 40 are employed which extend from the corner for a short distance in each direction within the sash members and serve also as an interior anchorage for the fastening screws by which the lock is held in place. As a further 80 means of securing the lock to the sash members the lock is advantageously provided with integral studs 41, 41 and with an integral hook stud 42. The sash rail is likewise provided in its upper edge with an 85 elongated slot 43 and the sash stile with a pair of slots adapted to receive the lugs 41. In assembling the lock with the sash the lug 42 is first dropped through the slot 43 and the lock then moved to the left causing 90 the hook 42 to engage beneath the upper wall of the rail and its corner insert 40 while the lugs 41 at the same time enter the slots in the stile provided for their reception. It will thus be seen that the lugs 41 and 42 95 sustain the lifting strain which is applied to the lock in operating the sash and that the screws 36, 37 and 38 are relieved almost entirely of shearing strain.

In the manufacture of sash from brass it 100 is important that the gauge of the metal employed be as low as possible in order to reduce the weight and consequent cost of material. The stiles of narrow sash are protected against rough usage by being enclosed 105 almost entirely between the window stops but the cross rails, and especially the lower rail, not being thus protected are liable to deformation in service, in the raising and lowering of the window by means of improvised implements, undue pressing against same, or by falling forcibly upon cinders or other hard particles upon the sill. In order to provide in the lower rail sufficient 110 rigidity to withstand rough usage and yet avoid the use of heavy gauge brass I provide the lower rail throughout its length with an inner reinforcement 44 of steel or the like which immediately abuts and supports the side, top and desirably the bottom walls of

the rail as shown in Figs. 2 and 3 and also in Fig. 7. For affording suitable anchorage for the glazing bead and retaining screws I also preferably employ similar interior 5 reinforcing tubes in the stiles and top cross rail.

In Figs. 6 to 8 inclusive a lock of the same general type is shown as mounted in an improved manner upon the fixed bead 23 of the several members, the same being secured 10 in position by means of screws 45 and 46 which pass through the fixed bead into the inner reinforcement 44. This renders possible the employment of a very narrow lower 15 rail while causing the lock to clear the sill coping 47. In this form of construction the removable glazing bead is in the form of a rigid angle strip having one portion 48 secured to the edge wall of the sash by 20 means of the screws 49 and another portion 50 bearing upon an elastic packing member 51 which surrounds the edge of the glass whereby the glass is held securely in place 25 against the fixed bead 23. It will be observed that in these figures, as also in certain of the other figures, the angle between 30 the two parts of the glazing bead is greater than the angle which the underlying face of the sash makes with the glass and the axis of the securing screws is at such an inclination as to provide for the rocking of the bead as on a fulcrum to cause the same to press against the glass under the action of the screw and also to grip and lock the screw by the back pressure of the strip. On 35 the sash stiles the removable glazing bead has combined therewith a weather strip in the form of a resilient metal member having one portion 52 secured to the sash and to the glazing bead by the screws 49 and 40 another portion 53 extending adjacent the side face of the stile and pressed towards the stile by the spring action which is emphasized by its beaded portion 54. Between 45 the portion 53 of the weather strip and the side face of the stile is housed the sash stop 55 so as to effectually preclude the entrance of dust, air or water around said stop and sash to the interior of the apartment, this 50 action being supplemented by the drawing of the sash under the action of the strip 53, snugly against the outer stops 55.

In Fig. 9 a slight modification is shown in which the removable glazing bead and the weather strip are combined in one, the 55 glazing bead in this instance being in itself resilient as distinguished from the rigid strip shown in Fig. 8.

In Fig. 10 is illustrated the manner in which the corner connection is formed between the combined glazing bead and weather strip of the stile and the glazing bead of the rail, the miter joint 56 between the two members extending throughout the glazing bead portion only and leaving the weather strip portion intact to extend to the point

57 near the bottom of the sash. In this figure also is illustrated the manner in which the lower end of the stop 55 is cut away in the line 55^a to prevent the trapping of water behind the same, the cut-away portion being 70 covered in the closed position of the sash by the lower end of the weather strip 53.

Having reference to Figs. 11, 12 and 13, a form of construction is shown in which a rigid glazing bead 58 is employed upon that 75 side of the sash which receives the lock. In this instance the glazing beads extend along the rail and stile to a meeting point, the end of one abutting against the edge of the other as shown in dotted lines in Figure 11. The lock, instead of performing the function of glazing beads at the corner, overlies the beads and is permanently attached thereto as by 80 rivets 59, and the lock is likewise secured through the glazing beads to the interior reinforcing tubes and the inner corner reinforcements 40 by the screws 60. It is also secured to the side face of the rail by male and female screw 61 which transfixes the 85 lock, rail, interior reinforcing tubes and interior and corner reinforcements. 90

In these figures the lock is also shown as adapted to a construction in which is employed a weather stripping 62 comprising a 95 spring strip folded upon itself and inserted between the edge of the stile and the bottom of the guide and also between the side face of the stile and the stop 63 with the beaded portion 64 projecting beyond the stop 63. In order to enable this form of weather stripping to be employed in connection with the lock the plunger 65 of the latter is offset 100 sufficiently from the side face of the sash to clear the projecting beaded portion 64 of the weather strip as clearly shown in Fig. 13. 105

In that form of construction just described the lock and removable glazing bead are removed as an entirety from the bottom rail and stiles of the sash when it is desired to renew the glass, the lock and glazing beads 110 being held permanently in assembled relation by means of the rivets 59.

In Figures 14 to 18 inclusive is shown a lock mounted upon the fixed bead of the sash in a manner differing somewhat from that shown in Figures 1, 2 and 3. Here the lock is provided with an integral downwardly depending lug or wing portion 66 and with a laterally extending lug 67, the stile being provided with a slot 68 adapted to receive the lug 67 and the rail being provided with an elongated slot 69 of a length at least equal to the width of the lug 66 plus the length of the lug 67. The lock is adapted to be assembled by dropping a lug 66 into the slot 69 and then moving the lock to the left so as to cause the lug 67 to enter the slot 69. The male and female screw 70 is then inserted, transfixing the walls of the sash rail, the interior reinforcement and the lug, 120 125 130

- the removable glazing bead in the form of a flat strip 71 being likewise attached at this point by means of the screw 70. In Fig. 16 is shown the glazing bead 71 combined with 5 a form of weather stripping similar to that shown in Fig. 8. Herein the outer face of the glazing bead 71 is flush with the side face of the stile and is thus enabled to extend within the space between the stops.
- 10 In the form of construction here shown, separate corner reinforcing angles 40 are dispensed with and the internal stiffening members 44 are applied interiorly of both the rails and stiles, the ends of the said stiffening members within the rails extending into and across the ends of the stiles and the members 4 of the stiles extending to and abutting against those of the rails, a fit being secured by mitering or coping the ends where necessary; or the meeting ends of the members may one enter the other and be suitably joined to each other and to the outer sash shell. In either case the whole joint may be 20 sweated together by dipping whereby the contacting surfaces of the stiffening members 44 will be joined to each other and to the sash shell at the corner.
- 25 In Fig. 19 is illustrated a resilient glazing bead which combines the U-shaped glass-receiving portion of the glazing bead shown in Fig. 5 with an exterior resilient portion 72 which is substantially flush with the side face of the stile as in Fig. 16. This portion 72 of the bead terminates in an inturned underlying portion 73 and held in place with reference to the stile by means of the male and female screw 74 which transfixes the stile at this point.

- 30 Fig. 20 shows a further modification in which the fixed glass supporting bead 23^a is formed by interlocked edges of the metal shell forming the sash member, which need not be permanently joined as by soldering or welding but which are maintained in interlocked engagement by the outward or expanding pressure of the interior reinforcing member which is driven into the shell and which also serves as an anchorage for the glazing bead screws 49.
- 35 40 Herein the term lock is meant to include devices generally for operating the sash, whether carrying a plunger for holding the sash in adjusted position or merely finger pieces for raising and lowering the same.
- 45 50 I claim:

- 60 1. The combination with sash members connected to form a sash corner and having on one side a fixed glass-retaining bead, of a lock disposed on that side of the sash opposite said bead with a portion abutting the glass margin, and a removable glazing bead secured to the sash marginally of the glass.
- 65 2. The combination with sash members connected to form a sash corner and having

on one side a fixed glass-retaining bead, of a lock disposed in the corner on that side of the sash opposite said bead with a portion overlying the inner edge of the sash and abutting the horizontal and vertical glass margin, and a removable glazing bead secured to the sash marginally of the glass with its end abutting the lock.

3. The combination with sash members connected to form a sash corner and having 75 on one side a fixed glass-retaining bead, of a lock disposed in the corner on that side of the sash opposite said bead, with a portion overlying the inner edge of the sash and supporting the horizontal and vertical glass 80 margin, and removable glazing beads secured to the sash marginally of the glass and cooperating with the lock to support the glass margin.

4. The combination with sash members 85 connected to form a sash corner, of a lock disposed in the corner with a portion overlying the interior edge of the sash adjacent the glass, and having an integral portion penetrating and underlying a portion of the 90 sash and being thereby interlocked therewith in a manner to prevent a right line withdrawal of the lock from the sash.

5. The combination with sash members connected to form a sash corner, of a lock 95 disposed in the corner with a portion overlying the interior edge of the sash adjacent the glass, the sash member having a slot, a hooked lug extending from the lock and adapted to enter the slot and interlock with 100 the sash, and removable fastening means to prevent the withdrawal of the lug.

6. The combination with sash members connected to form a sash corner, of a lock 105 disposed in the corner with a portion overlying the interior edge of the sash adjacent the glass, the sash member having a slot, a hooked lug extending from the lock and adapted to enter the slot and interlock with 110 the sash, and removable fastening means transfixing the lock and the side of the sash member and lug to prevent the removal of the latter.

7. The combination with sash members connected to form a sash corner and having 115 on one side a fixed glass retaining bead, and spring weather stripping disposed between the sash and members and the window stops and having a portion projecting beyond the stop, of a lock disposed on that side of the 120 sash opposite said fixed bead with a portion abutting the glass margin to press the same against the fixed bead, and a lock plunger offset from the side face of the sash a distance sufficient to clear the projecting portion of the weather stripping.

8. In metal sash construction, the combination of a sash rail and stiles formed of thin metal, of a relatively heavy metal reinforcement disposed within and extending 125

substantially the full length of the rail and supporting the walls thereof.

9. In metal sash construction, the combination of a sash rail and stiles formed of thin metal, of a relatively heavy metal reinforcement disposed within and extending substantially the full length of the rail and supporting the walls thereof, and L-shaped reinforcements disposed within and forming 10 a connection between the adjacent ends of the stiles and reenforced rail.

10. In metal sash construction, the combination with sash members having on one side a fixed glass-retaining bead, of a removable glazing bead having a U-shaped portion along one margin with inwardly sprung sides adapted to receive the edge of the glass, and exterior portions along the other margin adapted to overlie the edge 20 of the sash and the outer margin of the glass in planes at slight angles to the planes thereof.

11. In metal sash construction, the combination with sash members having on one side a fixed glass retaining bead, of a removable glazing bead having a U-shaped portion with inwardly sprung sides and an oblique bottom adapted to receive and grip the edge of the glass, exterior inclined and 30 substantially horizontal portions adapted to overlie the inner edge of the sash and the outer margin of the glass, and means for securing the glazing bead to the sash.

12. In metal sash construction, the com-

bination with sash members having on one side a fixed glass retaining bead, of a removable glazing bead having a U-shaped portion with inwardly sprung sides and an oblique bottom adapted to receive and grip the edge of the glass and to cushion the same 40 both edgewise and transversely, exterior inclined and substantially horizontal portions adapted to overlie the inner edge of the sash and the outer margin of the glass, and means for securing the glazing bead to the 45 sash.

13. The combination with sash members connected to form a sash corner and having on one side a fixed glass-retaining bead and sash lock disposed within the inner edge of 50 the sash opposite said bead and over-lapping the adjacent side of the glass.

14. In a metal sash, the combination with an outer thin shell of superior metal such as brass, of an inner stiffening and supporting lining of inferior metal such as steel 55 extending substantially throughout the shell, a lock member mounted on the shell and fastening members extending through the shell into the inner lining.

In testimony whereof I have hereunto signed my name in the presence of two subscribing witnesses.

GEORGE H. FORSYTH.
